UNITED STATES PATENT OFFICE.

ROBERT KENNEDY AND GEORGE KENNEDY, OF NEW WESTMINSTER, BRITISH COLUMBIA, CANADA.

PERFORATOR FOR PRINTING-PRESSES.

SPECIFICATION forming part of Letters Patent No. 380,578, dated April 3, 1888.

Application filed June 6, 1887. Serial No. 240,412. (No model.)

To all whom it may concern:

Be it known that we, ROBERT KENNEDY and GEORGE KENNEDY, both of New Westminster, in the Province of British Columbia and Dominion of Canada, have invented a new and Improved Perforator for Printing-PresSES, of which the following is a specification, reference being had to the annexed drawings, forming a part thereof, in which—

10 Figure 1 is a side sectional elevation of a part of a printing-press to which our improvement has been applied. Fig. 2 is an enlarged transverse section taken on line $x-x$ in Fig. 1. Fig. 3 is an enlarged transverse section taken 15 on line $y-y$ in Fig. 1. Fig. 4 is a plan view of one end of the perforator, and Fig. 5 is a yielding contact for operating the perforator.

Similar letters of reference indicate corresponding parts in all the views.

20 The object of our invention is to provide an efficient device for attachment to printing-presses for perforating blank checks, receipts, &c., simultaneously with the printing thereof.

Our invention consists in an oscillating bar 25 carrying a series of perforating-teeth and adapted to be supported in the form of the printing-press; also, in the combination therewith of devices for oscillating the perforating-bar, all as hereinafter more fully described.

30 The body of the perforator is formed of a bar, A, of metal, having in the upper surface thereof a semicircular groove, a, to which is fitted a cylindrical bar, B. To one end of the bar A is secured a block, C, provided with a 35 dowel, c, entering a hole in the end of the bar A.

The bar B is journaled at one end in a lip, d, projecting outwardly from the block C, and the opposite end of the bar B is journaled in 40 a lip, e, formed on the end of the bar A. The block C is provided with a chamber, f. To the journal of the rocking bar B, inside of the chamber f, is secured a pinion, g, and in the said chamber is pivoted an intermediate pinion, h, engaging the pinion g. In the side of the chamber f there is a guide, i, to which is fitted a rod, j, carrying a plate, k, to which is secured a rack-bar, l, arranged to engage the intermediate pinion, h.

50 To the upper end of the rack-bar l is secured

a finger, m, which projects through an opening in the side of the chamber f and extends over the chase D, in which the form is locked. Between the plate k and the wall of the chamber f is placed a spiral spring, j', which surrounds 55 the guide i and tends to push the plate k and rack-bar l outward. The finger m is protected by a guard-plate, n, projecting from the block C, and extending over the finger and over the chase.

The bar B is provided with a series of perforating-teeth, o. The perforating device is operated by a contact-piece, E, (shown in detail in Fig. 5,) which consists of a right-angled plate, F, provided with clips p, for receiving 65 the ends of a bowed spring, G, which is provided at the center thereof with a block, q. The contact-piece is held in place upon the platen of the printing-press by inserting the right-angled plate F between the clamp r and 70 the platen s, in position to allow the block q to project through an aperture, t, in the guard n and touch the finger m before the form comes into contact with the paper carried by the platen. The pressure of the block q upon the 75 finger pushes in the rack l, imparting rotary motion to the pinion h, which is transferred to the pinion g and turns the bar B through one-quarter of a revolution, bringing the perforating-teeth o into the position of use. The elasticity of the spring G permits of a certain movement of the platen or the bed of the press after the perforator is brought into position for use, so that the perforating-teeth are in a fixed position when they come into contact 80 with the paper. This construction also permits of the withdrawal of the perforator from the paper before the perforator is returned to its original position.

When the finger m is relieved from the pressure of the block q, the spring j', surrounding the guide i, pushes the rack l forward, and thus returns the perforator to the point of starting, with the teeth o resting upon the surface of the bar A, so that the roller as it passes over the 95 type is not injured by the teeth of the perforator and the inking of the perforating-teeth is avoided.

The perforator is applied to a printing-press by locking it up in the form with the type. 100

Having thus fully described our invention, we claim as new and desire to secure by Letters Patent—

1. In a perforator for printing presses, an oscillating bar provided with a series of perforating-teeth, and means for rocking the bar to bring the teeth into the position of use, substantially as described.

2. In a perforator for printing presses, the combination of the bar A, provided with the longitudinal semicircular groove a, the bar B, pivoted on the bar A and provided with a series of perforating-teeth, o, the pinion g, secured to one of the bearings of the bar B, the intermediate pinion, h, the spring - actuated rack l, provided with the finger m, and means, substantially as shown and described, for pushing in the said rack.

3. In a perforator for printing-presses, the

combination of the bar A, provided with the longitudinal semicircular groove a, the bar B, pivoted on the bar A and provided with a series of perforating-teeth, o, the pinion g, secured to one of the bearings of the bar B, the intermediate pinion, h, the spring - actuated rack l, provided with the finger m, and the yielding contact formed of the plate F and bowed spring G, provided with the block q, substantially as described.

4. The combination, with the finger m, rack l, spring j', pinions g h, and mechanism connected therewith, of the apertured guard-plate n, substantially as described.

ROBERT KENNEDY.
GEORGE KENNEDY.
